UNITED STATES PATENT OFFICE.

PAUL H. SMITH, OF COLUMBUS, OHIO.

TRUNK.

SPECIFICATION forming part of Letters Patent No. 606,431, dated June 28, 1898.

Application filed February 10, 1898. Serial No. 669,737. (No model.)

To all whom it may concern:

Be it known that I, PAUL H. SMITH, a citizen of the United States, residing at Columbus, in the county of Franklin and State of Ohio, have invented certain new and useful Improvements in Trunks; and I do hereby declare the following to be a full, clear, and exact description of the invention, such as will enable others skilled in the art to which it appertains to make and use the same.

The object of my present invention is to provide improved devices for supporting and elevating the tray of a trunk, and its special purpose is to enable the tray to be removed without removing its support.

In the accompanying drawings, illustrating an embodiment of my invention, Figure 1 is a vertical section taken longitudinally through the end of a trunk containing my improvements. Fig. 2 is a perspective view of a tray-supporting tube, the lower portion being broken out to show details of construction. Fig. 3 is a bottom plan view of the tray-supporting bracket; and Fig. 4 is a sectional view of the tubes, taken on line xx of Fig. 1 and looking up.

The outer tube 1 for containing the tray-supporting tube and bracket, with a slot connecting with a chamber for containing and supporting pulleys 1^a , may be substantially the same and fitted to the end wall of the trunk, as shown in my application for patent filed December 16, 1897, Serial No. 662,194.

The inner tube 2, which fits neatly in the tubular portion 1, but so as to slide vertically therein, has its lower end cut with a T-slit to allow the bending outward of tongues 2^a , that project toward the pulley-chamber of the outer tube 1. These tongues serve to prevent the rotation of the tube 2 in the outer tube 1, but do not prevent said tube 2 from being raised or lowered vertically. In the lower portion of the said tube and just above the tongues 2^a is placed a cylindrical block 3, having a hole 3^a through its center, said block being secured by means of a pin 3^b , passed through the tube into the block. The lower end of the inner side of the tube 1, as well as the corresponding part of the tube 2, has a small opening or notch to allow the passage of a cord.

The bottom of the tray is furnished with a

metallic bracket, as shown in Fig. 3, consisting of a bar 4, that has at its outer end two upright arms 4^a and 4^b , that fit and are secured in tenons cut in opposite sides of the end board of the tray 5, and the inner end of said bracket-bar 4 has a depressed portion 4^c to form a recess to receive a wooden bar 5^a , that extends transversely across the bottom of the tray. The metallic bracket-bar 4, with its upright arms 4^a and 4^b , together with the wooden bar 5^a , make a good brace for the tray 5. The under side of the bracket-bar 4 is provided with a socket 4^d to fit upon the upper end of the tube 2, that projects beyond the upper end of the tube 1, and to enable the easy finding of the upper end of said tube 2 when the tray is to be placed thereon the said socket is flared at its lower end. The under side of this bracket-bar is also made with a strengthening web or strip 4^e , extending between the socket 4^d and depressed portion 4^c , as well as along the under side of the bracket at the opposite side of the socket.

In practice a cord, preferably of wire, is attached to a block 3 and passed out through the opening between the tongues in the lower end of the tube 2, then upward in the pulley-chamber, over the upper pulley, and downward over the lower pulley in said chamber, thence inward through the openings between the aforesaid tongues and the small openings in the inner sides of the lower ends of the tubes 1 and 2, and across the bottom of the trunk to a device by means of which the cord may be drawn. When the cord is drawn, the tube 2 and bracket are raised, and with them the tray, which may be swung outward on tube 2, displaying the interior of the trunk.

If at any time it is desired to remove the tray from the trunk, it may be simply lifted off the end of the tube 2 without disturbing or removing any of the other parts, and in replacing the tray the flared socket on the bottom of the bracket-bar 4 causes the tray to be directed into its proper position on the tube 2.

What I claim, and desire to secure by Letters Patent, is—

1. A bracket-supporting tube having at its lower end a slot at one side and at the opposite side having a T-slit, the parts being bent out to form tongues or guides to prevent ro-

tation, and just above said tongues or guides on the inside of said tube a cylindrical block with a hole through its center held in position by means of pins, substantially as described.

5 2. A removable tray-supporting bracket having a horizontal bar, this bar having at one end two upright arms, at its other a depressed portion which provides a rest for a cross-arm and having on its under side a web

or a strip and a socket flared at its lower end, 10 substantially as described.

In witness whereof I have hereunto set my hand in the presence of two witnesses.

PAUL H. SMITH.
